CONVERSION OF HYDROCARBON OILS

Kenneth Swartwood, Chicago, Ill., assignor to
 Universal Oil Products Company, Chicago, Ill.,
 a corporation of Delaware

Application July 15, 1933, Serial No. 680,556

8 Claims. (Cl. 196—49)

This invention particularly refers to an improved process of the type wherein a hydrocarbon oil charging stock of relatively wide boiling range, such as crude petroleum, is separated by distillation into low-boiling and high-boiling fractions, each of which are subjected to independently controlled selected conversion conditions in the same cracking system and wherein the residual conversion products of the process are reduced to coke; the process being operated for the production, primarily, of high yields of light liquid products such as motor fuel of high antiknock value and minor yields of coke and gas.

15 The distinguishing feature of the present invention resides in the novel and advantageous treatment of the high-boiling fractions of the charging stock, which, after being separated from the lower boiling fractions, are subjected to further distillation in a low-pressure vaporizing zone of the cracking system wherein the heavy components of said high-boiling fractions of the charging stock are separated from its lighter vaporous components and commingled with the 20 residual liquid conversion products of the process while the vapors from this zone, including vaporous conversion products of the process and said vaporous components of the high-boiling fractions of the charging stock, are subjected to fractionation for the formation of reflux condensate which is returned to a heating coil of the cracking system for further conversion.

The process of the present invention is particularly advantageous for the treatment of 25 charging stocks of relatively wide boiling range, for example such as crude petroleum or other oils containing appreciable quantities of both low-boiling fractions and high-boiling materials of a heavy residual nature, since, in accordance with 30 the features of the present invention, I avoid passage of the heavy residual components of the charging stock through a cracking coil, thus avoiding the excessive coke and gas formation which would result from the conversion of these 35 materials under the high temperature and pressure conditions required for the production of maximum yields of desirable light liquid products from the lower boiling fractions of the charging stock.

40 I am aware that other processes have been proposed for the separation of oils of relatively wide boiling range into low-boiling and high-boiling fractions, conversion of the low-boiling fractions under relatively severe conversion conditions and further distillation of the high-boil-

ing fractions in the same cracking system under relatively mild or even non-cracking conditions, but the present invention differs from such processes in that, in the present invention, the heavy residual components of the high-boiling fractions 5 of the charging stock which are unsuitable for conversion at high-temperature and pressure are subsequently reduced to coke, together with the residual products of the cracking operation. Vaporous products from the coking operation as 10 well as the vaporous conversion products of the process and the vapors resulting from said further distillation of the high-boiling fractions of the charging stock are subjected to fractionation and the resulting reflux condensate, comprising 15 the insufficiently converted components of the total vaporous products of the process, are subjected to further conversion in the same system, preferably under milder heating conditions than those employed for the conversion of the low-boiling fractions of the charging stock, which latter are utilized as a heat carrying medium for the coking operation. This method of operation permits the production of high yields of light 20 liquid products such as motor fuel of high antiknock value with minimum yields of heavy residual products and gas and it will be apparent that the various steps of the process all cooperate to produce the final desired results, the novelty of the present invention residing in the advantageous combination of the various features provided.

25 One embodiment of the present invention comprises subjecting a hydrocarbon oil of relatively wide boiling range to distillation whereby it is 30 separated into low-boiling and high-boiling fractions, subjecting the latter to further vaporization, subjecting the unvaporized residual oil to 35 coking, subjecting low-boiling fractions of the charging stock to pyrolytic conversion and utilizing the resulting highly heated conversion 40 products as a heat carrying medium to assist the coking operation, subjecting the vaporous products of the process resulting from conversion, coking and said further vaporization of the high-boiling fractions of the charging stock to fractionation 45 whereby components boiling above the range of the desired final light distillate product of the process are condensed as reflux condensate, subjecting the reflux condensate to independently controlled conversion conditions of elevated 50 temperature and superatmospheric pressure and commingling the resulting products at substantially reduced pressure with said high-boiling fractions of the charging stock whereby 55

to effect said further vaporization of the latter and the liquid conversion products.

The accompanying diagrammatic drawing illustrates one specific form of apparatus in which the process may be accomplished. It will be understood that the invention is not limited to this nor to any other specific form of apparatus.

Referring to the drawing, raw oil charging stock for the process, preferably comprising an oil of 10 relatively wide boiling range containing an appreciable quantity of both low-boiling and high-boiling fractions such as crude oil, is supplied in heated state through line 1 and valve 2 to distilling and fractionating column 3. Heating of 15 the charging stock to the temperature required for its distillation may be accomplished in any well known manner, not illustrated, for example, by heat recovered from hot vaporous and/or liquid products of the process or by heat from an external source. Heating of the charging stock may 20 be accomplished at any desired pressure and column 3 is preferably operated at substantially atmospheric pressure although superatmospheric pressure or partial vacuum may be employed in 25 this zone, when desired. The charging stock is separated in column 3 into low-boiling and high-boiling fractions.

When the charging stock contains any appreciable quantity of motor fuel or motor fuel fractions 30 of satisfactory antiknock value they may be removed, together with any gas from the distilling operation, from the upper portion of column 3 through line 4 and valve 5 to condenser 6. The resulting distillate and gas passes through 35 line 7 and valve 8 to collection and separation in receiver 9. Gas may be released from the receiver through line 10 and valve 11. Distillate may be withdrawn through line 12 and valve 13 to storage or elsewhere, as desired. In this case 40 any higher boiling motor fuel fractions of inferior antiknock value and/or, when desired, other light oils such as naphtha, kerosene, kerosene distillate, light gas oil and the like are separately removed as one or a plurality of side 45 streams from any suitable point in column 3, for example, through line 14 and valve 15 to pump 16 to be supplied therefrom to conversion in heating coil 21, as will be later more fully described. When no appreciable quantity of motor fuel or 50 motor fuel fractions of satisfactory antiknock value are contained in the charging stock, the low-boiling oils to be supplied to heating coil 21 may be removed from the upper portion of column 3 through line 4 and collected as distillate in 55 receiver 9, in the manner previously described, to be withdrawn therefrom through line 17 and valve 18 to pump 16. In the latter case it is also within the scope of the present invention, instead of subjecting the overhead vaporous product from 60 column 3 to condensation and separating the resulting distillate and gas, to supply the total vaporous products direct to heating coil 21 by means of a suitable pump or compressor and the required connecting lines which for the sake of 65 simplicity, are not shown in the drawing.

High-boiling fractions of the charging stock, comprising its components boiling above the range of the lighter oils supplied to pump 16 and including any components of the charging stock 70 of a heavy residual nature, are withdrawn from the lower portion of column 3 through line 22 and valve 23 to pump 24 by means of which they are fed through line 25 and valve 26 into vaporizing chamber 27, commingling, in the case illustrated, in line 25 with hot conversion products

from reaction chamber 28, as will be later more fully described, although it is within the scope of the present invention to separately introduce these materials into chamber 27 at any desired point. Further vaporization of the high-boiling 5 fractions of the charging stock is accomplished in chamber 27 by means of heat derived from the hot conversion products from chamber 28 supplied to this zone and, when desired, by other means which will be later more fully described. The 10 residual liquid remaining unvaporized in chamber 27, comprising both the heavy residual components of the charging stock and residual liquid conversion products of the process remaining unvaporized in this zone are withdrawn therefrom 15 through line 31 and valve 32 and are supplied through lines 34 and 34' controlled, respectively, by valves 35 and 35' into the respective coking chambers 33 and 33'. The vapors from chamber 27, including vaporous conversion products 20 from chamber 28 supplied to this zone and vapors derived by further vaporization of the high-boiling fractions of the charging stock from column 3 and liquid conversion products from chamber 28, pass from chamber 27 through line 36 25 and valve 37 to fractionation in fractionator 38, together with vaporous products from the coking zone, as will be later more fully described.

The low-boiling oils supplied to pump 16 are fed therefrom through line 19 and valve 20 to heating coil 21 wherein they are heated to the desired conversion temperature, preferably at a substantial superatmospheric pressure by means of heat supplied from a furnace 39 of any suitable form. When the oil supplied to heating coil 21 30 comprises a substantial proportion of materials within the boiling range of motor fuel the conditions of conversion temperature, pressure and time employed in the heating coil are preferably such as to effect a substantial improvement in 35 the motor fuel characteristics of this material, particularly with respect to its antiknock value, without excessively altering its boiling range. Such conditions may be selected which are also suitable for the conversion of higher boiling oils 40 such as naphtha, kerosene or kerosene distillate, light gas oil and the like and it is also within the scope of the invention to include any such components of the charging stock with the motor fuel 45 or motor fuel fractions supplied to heating coil 21 50 or to supply thereto only materials boiling above the range of motor fuel, such as previously indicated. Regardless of the specific low-boiling oil supplied to heating coil 21 and the specific conversion conditions employed therein, the 55 nature of the heated products discharged therefrom and the temperature to which they are heated, within the scope of the present invention, it is necessary to select conditions which will be satisfactory for accomplishing coking of the 60 residual oils supplied to the coking chambers.

The highly heated products are discharged through heating coil 21 through line 40 and valve 41 and are introduced through lines 42 and 42' controlled, respectively, by valves 43 and 43' into 65 the respective coking chambers 33 and 33' entering the coking chambers at one or a plurality of any desired points therein, although only a single point of introduction to each chamber is shown in the drawing. The heated low-boiling oils 70 preferably enter below the level of residual material in the coking zone and come into direct contact with the residual liquid supplied thereto, heating the latter to a sufficiently high temperature 75 to effect its reduction to coke under the low-

pressure conditions employed in this zone. Although two coking chambers are shown in the drawing it will be understood that one or any number of a plurality of such zones may be employed within the scope of the invention. A plurality of alternately operated coking chambers is preferred in order that one or more such zones may be cleaned and prepared for further operation while another or others are in use, although simultaneous operation of a plurality of coking chambers may be employed. Chambers 33 and 33' are provided with drain-lines 44 and 44', respectively, controlled by the respective valves 45 and 45'. These lines may also serve as a means of introducing steam, water or other suitable cooling medium into the bed of residual material in the coking zone after the operation of the chamber is completed in order to hasten cooling and facilitate cleaning of the chamber.

Vapors evolved by the coking operation as well as vaporous products resulting from conversion of the low-boiling oils in heating coil 21 are withdrawn from chambers 33 and 33' through the respective lines 46 and 46' controlled, respectively, by valves 47 and 47' and may pass through line 48 and valve 68 to fractionation in fractionator 38 or, when desired, a regulated portion or all of the relatively hot vapors from the coking chambers may be introduced into vaporizing chamber 27, for example, through line 69 and valve 70 or at any other desired point, preferably coming into direct contact with the residual liquid in chamber 27 for the purpose of increasing its temperature and assisting its vaporization to the desired degree.

Components of the vaporous products supplied to fractionator 38, boiling above the range of the desired final light distillate product of the process are condensed in this zone as reflux condensate. Fractionated vapors of the desired end-boiling point are withdrawn, together with uncondensable gas, from the upper portion of fractionator 38 through line 49 and valve 50 and are subjected to condensation and cooling in condenser 51. The resulting distillate and gas passes through line 52 and valve 53 to collection and separation in receiver 54. Uncondensable gas may be released from receiver 54 through line 55 and valve 56. The distillate may be withdrawn from this zone through line 57 and valve 58 to storage or to any desired further treatment and it may, when desired, be blended with any motor fuel components of the charging stock of satisfactory anti-knock value collected, as previously described, in receiver 9, in which case the blended material comprises the final motor fuel product of the process.

The usual method of controlling fractionation in fractionator 38 and column 3, for example, such as recirculating a portion of the distillate from the receivers 54 and 9 to the upper portion of the respective fractionating zones are entirely within the scope of the present invention, although the well known means whereby this may be accomplished are not illustrated in the drawing.

The reflux condensate formed in fractionator 38, comprising insufficiently converted components of the total vaporous conversion products of the process and components of the high-boiling fractions of the charging stock which are vaporized in chamber 27 and subsequently subjected to fractionation in fractionator 38, are withdrawn from the lower portion of this zone through line 59 and valve 60 to pump 61 by means

of which they are fed through line 62 and valve 63 to conversion in heating coil 64.

Heating coil 64 is located in a furnace 65 of any suitable form by means of which sufficient heat is supplied to the oil to bring it to the desired conversion temperature, preferably at a substantial super-atmospheric pressure and the heated oil is discharged through line 66 and valve 67 into reaction chamber 28.

Chamber 28 is also preferably maintained at a substantial superatmospheric pressure and, although not illustrated in the drawing, is preferably well insulated to prevent the excessive loss of heat by radiation so that conversion of the heated products from heating coil 64, and more particularly their vaporous components, may continue in the reaction chamber. In the case here illustrated, both vaporous and liquid conversion products are withdrawn in commingled state from the lower portion of chamber 28 through line 29 and valve 30 and are introduced through line 25 into vaporizing chamber 27, which is preferably maintained at a substantially reduced pressure relative to that employed in the reaction chamber in order to effect further vaporization in this zone of the liquid conversion products from chamber 28 and the high-boiling fractions of the charging stock from column 3.

In an apparatus such as illustrated and above described, preferred operating conditions for the process may be as follows: Heating of the charging stock, prior to its introduction into the distilling and fractionating column may be accomplished at any desired pressure ranging, for example, from substantially atmospheric to 150 pounds, or thereabouts, per square inch and the temperature to which it is heated may range, depending upon the nature of the charging stock, the pressure employed and the desired separation of the low-boiling and high-boiling fractions, from 450 to 750° F., or thereabouts. Substantially atmospheric, subatmospheric or a super-atmospheric pressure, preferably not in excess of 100 pounds, or thereabouts, per square inch may be employed in the distilling and fractionating column and may be substantially equalized or reduced in the succeeding condensing and collecting equipment. The heating coil to which the low-boiling fractions of the charging stock are supplied may utilize a conversion temperature measured at the outlet therefrom within the range of 900 to 1100° F., or thereabouts, preferably with a substantial superatmospheric pressure at this point in the system of from 300 to 1000 pounds, or thereabouts, per square inch although, when desired, lower pressures down to substantially atmospheric may be employed in this zone. The coking chambers preferably employ substantially atmospheric or a low superatmospheric pressure not in excess of 100 pounds, or thereabouts per square inch. The heating coil to which reflux condensate from the fractionator of the cracking system is supplied may utilize an outlet conversion temperature within the range of 800 to 950° F., or thereabouts, preferably with a substantial superatmospheric pressure of the order of 100 to 500 pounds per square inch. This pressure preferably is substantially equalized in the succeeding reaction chamber, although a somewhat reduced pressure may be employed in this zone, when desired. The vaporizing chamber is preferably operated at substantially reduced pressure relative to that employed in the reaction chamber and

65
70
75

may range, for example, from 100 pounds, or thereabouts, per square inch, to substantially atmospheric. Pressures of from 100 pounds to substantially atmospheric may be employed in the fractionating, condensing and collecting portions of the cracking system.

As a specific example of one of the many possible operations of the process of the present invention as it may be practiced in an apparatus 10 of the type illustrated and above described, the charging stock may comprise a California crude of about 33° A. P. I. gravity containing less than 5 percent of material boiling up to 200° F., and approximately 30 percent of 400° F. which is 15 subjected to distillation at substantially atmospheric pressure and thereby separated into fractions boiling above and below approximately 620° F. The low-boiling fractions which comprise approximately 60 percent of the charging 20 stock are subjected to a conversion temperature of approximately 970° F. at a superatmospheric pressure of about 500 pounds per square inch and are introduced into direct contact with the residual material in the coking zone of the system. The high-boiling fractions of the charging 25 stock are supplied to the vaporizing chamber and reflux condensate from the fractionator, is subjected to a conversion temperature of approximately 930° F. at a superatmospheric pressure 30 of approximately 350 pounds per square inch in a separate heating coil. The succeeding reaction chamber is maintained at about the same pressure and a reduced pressure of approximately 30 pounds per square inch is employed in the vaporizing chamber as well as in the coking chambers 35 and the succeeding fractionating, condensing and collecting portions of the system. This operation may produce, per barrel of charging stock, about 65 percent of motor fuel having an antiknock 40 value equivalent to an octane number of approximately 75 and about 60 pounds of low volatile coke, the remainder being chargeable principally to uncondensable gas.

I claim as my invention:

45 1. A process for the conversion of hydrocarbon oils which comprises separating, by distillation, hydrocarbon oil charging stock for the process into low-boiling and high-boiling fractions, further separating from the high-boiling fractions 50 any heavy components of a residual nature unsuitable for conversion at elevated temperature and superatmospheric pressure, subjecting the latter to coking at low-pressure, subjecting the remaining lower boiling components of said high-boiling fractions of the charging stock to conversion 55 at elevated temperature and superatmospheric pressure, separating the resulting vaporous and residual liquid conversion products, subjecting the latter to coking together with said heavy 60 residual components of the high-boiling fractions of the charging stock, subjecting low-boiling fractions of the charging stock to independently controlled more severe conversion conditions and 65 contacting the resulting highly heated products with the residual materials undergoing coking for the purpose of assisting their reduction to coke.

2. A process for the conversion of hydrocarbon oils which comprises separating, by distillation, hydrocarbon oil charging stock for the process 70 into low-boiling and high-boiling fractions, further separating from the high-boiling fractions any heavy components of a residual nature unsuitable for conversion at elevated temperature and superatmospheric pressure, subjecting the latter to coking at low-pressure, subjecting the

remaining lower boiling components of said high-boiling fractions of the charging stock to conversion at elevated temperature and superatmospheric pressure, separating the resulting vaporous and residual liquid conversion products, subjecting the latter to coking together with said heavy residual components of the high-boiling fractions of the charging stock, subjecting low-boiling fractions of the charging stock to independently controlled more severe conversion conditions, contacting the resulting highly heated products with the residual materials undergoing coking for the purpose of assisting their reduction to coke, subjecting the vaporous products of the cracking and coking operations to fractionation whereby their insufficiently converted components are condensed as reflux condensate, subjecting fractionated vapors of the desired end-boiling point to condensation, recovering the resulting distillate and returning the reflux condensate to further conversion, together with said remaining lower boiling components of the high-boiling fractions of the charging stock.

3. A process for the conversion of hydrocarbon oils which comprises subjecting hydrocarbon oil charging stock for the process to fractional distillation whereby it is separated into low-boiling and high-boiling fractions, introducing the latter into a vaporizing chamber whereby its heavy components which remain unvaporized in this zone are separated from its lower boiling components, subjecting the latter to conversion temperature at superatmospheric pressure in a heating coil and communicating reaction chamber, separating the resulting vaporous and liquid conversion products and subjecting the latter to further vaporization at substantially reduced pressure in said vaporizing chamber, withdrawing unvaporized residual oil from said vaporizing chamber and introducing the same into a low-pressure coking zone, subjecting low-boiling fractions of the charging stock to independently controlled more severe conversion conditions in a separate heating coil, introducing the highly heated products into direct contact with the residual material in the coking zone for the purpose of assisting its reduction to coke, subjecting the vaporous products of the process to fractionation whereby their insufficiently converted components are condensed as reflux condensate, subjecting fractionated vapors of the desired end-boiling point to condensation, recovering the resulting distillate and returning the reflux condensate to the first mentioned heating coil for further conversion.

4. A process for the conversion of hydrocarbon oils which comprises subjecting hydrocarbon oil charging stock for the process to fractional distillation whereby it is separated into low-boiling and high-boiling fractions, introducing the latter into a vaporizing chamber whereby its heavy components which remain unvaporized in this zone are separated from its lower boiling components, subjecting the latter to conversion temperature at superatmospheric pressure in a heating coil and communicating reaction chamber, withdrawing both vaporous and liquid products from the reaction chamber and introducing them at reduced pressure into said vaporizing chamber whereby to effect said further vaporization of the high-boiling fractions of the charging stock as well as the liquid conversion products, withdrawing unvaporized residual oil from said vaporizing chamber and introducing the same into a low-pressure coking zone, subjecting low-boil-

- ing fractions of the charging stock to independently controlled more severe conversion conditions in a separate heating coil, introducing the highly heated products into direct contact with the residual material in the coking zone for the purpose of assisting its reduction to coke, subjecting the vaporous products of the process to fractionation whereby their insufficiently converted components are condensed as reflux condensate, subjecting fractionated vapors of the desired end-boiling point to condensation, recovering the resulting distillate and returning the reflux condensate to the first mentioned heating coil for further conversion.
5. A process for the conversion of hydrocarbon oils which comprises subjecting hydrocarbon oil charging stock for the process to fractional distillation whereby it is separated into low-boiling and high-boiling fractions, introducing the latter into a vaporizing chamber whereby its heavy components which remain unvaporized in this zone are separated from its lower boiling components, subjecting the latter to conversion temperature at superatmospheric pressure in a heating coil and communicating reaction chamber, separating the resulting vaporous and liquid conversion products and subjecting the latter to further vaporization at substantially reduced pressure in said vaporizing chamber, withdrawing unvaporized residual oil from said vaporizing chamber and introducing the same into a low-pressure coking zone, subjecting low-boiling fractions of the charging stock to independently controlled more severe conversion conditions in a separate heating coil, introducing the highly heated conversion products into direct contact with the residual material in the coking zone for the purpose of assisting its reduction to coke, introducing a regulated portion of the hot vaporous products from the coking zone into direct contact with the liquid in said vaporizing chamber for the purpose of assisting its vaporization, subjecting the vaporous products of the process to fractionation whereby their insufficiently converted components are condensed as reflux condensate, subjecting fractionated vapors of the desired end-boiling point to condensation, recovering the resulting distillate and returning the reflux condensate to the first mentioned heating coil for further conversion.
6. A conversion process which comprises subjecting reflux condensate, formed as hereinafter set forth, to cracking conditions of temperature and pressure in a heating coil and separating the same into vapors and unvaporized oil, in an enlarged chamber simultaneously partially distilling fresh charging oil for the process and sep-

arating a relatively light fraction therefrom, combining residual fractions of the charging oil with said unvaporized oil and subjecting the resultant mixture to distillation in a second enlarged chamber, subjecting said light fraction to independently controlled cracking conditions of temperature and pressure in a second heating coil and then contacting the same with said mixture to assist the distillation thereof, combining resultant vapors from said second chamber with vapors separated in the first-named chamber and fractionating the commingled vapors to condense heavier fractions thereof, supplying such condensed heavier fractions to the first-mentioned heating coil as said reflux condensate, and finally condensing the fractionated vapors.

7. A conversion process which comprises subjecting reflux condensate, formed as hereinafter set forth, to cracking conditions of temperature and pressure and separating the same into vapors and unvaporized oil, simultaneously partially distilling fresh charging oil for the process and separating a relatively light fraction therefrom, combining the unvaporized portion of the charging oil with said unvaporized oil and reducing the resultant mixture to coke, heating said light fraction to higher cracking temperature than the reflux condensate and then contacting the same with said mixture to assist the coking thereof, combining the vapors evolved from said mixture with the first-mentioned vapors and fractionating the thus commingled vapors to condense heavier fractions thereof, supplying such condensed heavier fractions to the first-named cracking step as said reflux condensate, and finally condensing the fractionated vapors.

8. A conversion process which comprises subjecting reflux condensate, formed as hereinafter set forth, to cracking conditions of temperature and pressure in a cracking zone and separating the same into vapors and residual oil in a separating zone, simultaneously partially distilling fresh charging oil for the process and separating a relatively light fraction therefrom, introducing the unvaporized portion of the charging oil into the separating zone and commingling the same therein with said residual oil, heating said light fraction to higher cracking temperature than said reflux condensate and then contacting the same with the commingled residual oil and unvaporized charging oil to distil this mixture to coke, subjecting the vapors thus formed and the first-named vapors to common fractionation to condense heavier fractions thereof, supplying such condensed heavier fractions to said cracking zone as said reflux condensate, and finally condensing the fractionated vapors.

KENNETH SWARTWOOD.
